UNITED STATES PATENT OFFICE.

ELBERT M. BRAXTON, OF FORT WORTH, TEXAS, ASSIGNOR OF ONE-HALF TO MABEL R. SPELLMAN, OF DALLAS, TEXAS.

GAS PRODUCER AND PROCESS.

1,424,077.

Specification of Letters Patent. Patented July 25, 1922.

Application filed November 18, 1921. Serial No. 516,147.

To all whom it may concern:

Be it known that I, ELBERT M. BRAXTON, a citizen of the United States, residing at Fort Worth, in the county of Tarrant and State of Texas, have invented certain new and useful Improvements in Gas Producers and Processes, of which the following is a specification.

This invention relates to gas producers for the production of gas from lignite and its by-products such as creosote and coal tar, and has for one of its principal objects the provision of a gas producer provided with a super-heater or means whereby the gas in its first or green state of production as it is formed by the combustion of the lignite, is heated by means of a super-heater to a very high temperature.

Another principal object of the invention is in the provision for feeding the fuel evenly and uniformly upon the fire-bed.

A further object of the invention is the provision for the cleaning, cooling and drying of the gas from impurities or extraneous matter, especially tarry substance or residue.

Other important features, such as a conical sectional revoluble and removable grate, auxiliary draft controlling and steam injecting means for the fire box, &c., will be more fully understood by reference to the following description taken in connection with the accompanying drawings forming part hereof in which—

Figure 1 is a vertical sectional view of a gas producing machine constructed in accordance with the invention.

Figures 2 and 3 are cross-sectional views of cylinders or tanks containing, respectively, coke and hay by preference, as a cleaning and drying means for the gas.

Figure 4 is a vertical sectional view taken on line 4—4, Figure 1, showing the invention in its interior arrangement as to the hopper and feeding means for the fuel.

Figure 5 is a cross-sectional view of the hopper taken on line 5—5 of Figure 1, and

Figure 6 is a cross-sectional view taken on line 6—6 Figure 1 through the fire-box and grate.

Referring more in detail to the drawings, in the construction and carrying out of the invention there is provided a base section or drum which forms an ash pit and draft chamber 1 and which is provided with an

opening normally closed by the usual ash 55 and draft door 2.

Within the draft chamber and ash pit 1 is an annular flanged support 3 resting upon the brackets 4—4. The support 3 has a raised portion or collar 5 which is provided with ball bearings to support and provide for the easy rotation of a platform 6. This platform as depicted in the drawing, Figures 1 and 6, supports a removable sectioned grate 6^a projecting upward into the fire-box in the form of a cone and which will be readily understood permits the clinkers and such matter as does not fall through the grate to roll down by gravity upon the platform 6 and may be raked off 70 and into the ash pit 1 from time to time as the fire is attended to, the doors 7—7 being provided for this purpose, and clearly shown in Figures 1 and 6. The platform 6 carrying the grate 6^a may be revolved in any manner, the simplest means and as shown in Figure 1, being by gear 6^b and pulley gear 6^c mounted upon a short shaft, the gear meshing with teeth on the underside of the platform 6.

Underneath the grate is arranged a tubular chamber or auxiliary draft pipe A which terminates into an upright member B closed at one end and provided with a covering C for protection. A damper D is provided, 85 and projecting within the chamber A is a steam pipe E which communicates with the interior of the water jacket 9 and is for the purpose of injecting steam or vapor into the fire-bed.

Seated upon the ash pit and draft chamber 1 is an upright, double-walled drum 8, the spaced inner and outer walls of which provide a water space 9 (referred to above) for the purpose of protection. This drum 95 8 constitutes the fire pot and collection chamber of the device.

Depending within the drum 8 and spaced from the inner walls thereof is an inverted frusto-conical tubular feeder 8^a, the lower 100 end of the wall of which is formed with radially disposed out-struck hoods 10 which communicate with the interior of the tubular feeder. The lower end of this feeder terminates just above the fire bed and its upper end is secured by rivets or otherwise to the annular support 11 formed with an outturned flange 12 which flange rests upon

a ring 13 seated upon the drum 8 and through which ring the annular support 11 projects.

A tubular container 14 has its lower end 5 threaded into or otherwise secured to the support 11 and its upper end is formed with a flaring mouth or hopper 15. The container 14 is provided with a magazine or fuel measure of cylindrical form comprising 10 two sections 16 and 17 arranged one within the other, the section 17 provided with two openings 18 and 19 and section 16 with one opening 20. Section 17 is secured to the inner wall of the container 14 by supports 15 21 and is open at one end for the reception of section 16, a bearing 22 being provided in section 17 for the axial pin 23 of section 16. The opposite end of section 16 of the fuel measure has a small shaft 24 seated in 20 a bearing 25 secured to the hopper 15 and this shaft carries a wheel 26 to rotate the sections in such a manner as to allow the openings 18 and 20 to register when a fresh charge of fuel is fed onto the grate, the 25 charge being deposited by rotating section 16 to register opening 20 with opening 19 which closes the opening 18 and deposits the fuel onto the fire bed. This operation may be performed by hand at certain periods 30 of time or when it is desired to drop a fresh charge of fuel onto the fire bed.

The container 14 is provided with an annular worm wheel 27 which meshes with a worm 28 driven by suitable means (not 35 shown) for rotating the container, hopper, and fuel measure. For the sake of clearness, however, it may be added that the container does not rotate continuously, but only at certain periods required for properly 40 feeding and distributing fuel onto the fire bed. This periodic rotation is provided by having the shaft 28^a divided and a clutch mounted on one end of the shaft, and by this means the motive power is connected 45 and disconnected with the worm 28 as required.

One of the principal features of the producer, the super-heater, is located slightly above the grate or fire bed, and shown at 29 50 in Figure 1. The super-heater, however, may if preferred be embedded in the fire bed or at any other point where the greatest amount of heat may act upon it. The super-heater is preferably formed with 55 short, cylindrical ends between which ends it is flattened to form a hollow, vertically arranged web connecting the ends. Pipes 30 communicate at suitable intervals with the interior of the drum 8, near the upper 60 end of said drum, and converge downwardly about the outside of the drum to take into one end of the super-heater. From the opposite end of this super-heater 29 a pipe 31 is provided for carrying away the green gas 65 for cleaning and washing it.

Pipe 31 communicates with an upright cylindrical tank 32. This tank, a cross-section of which is shown at Figure 2, is filled with coke by preference, which is supported upon a perforated grating 33. Below the grating 33 is a space 34 for water which space communicates by pipe 35 with a trap 36. At the top of the tank is a pipe 37 with a sprayer or distributor 37^a for water. Pipe 31 is provided on its end with an inverted scalloped edged cup 38 which is suspended in the water just far enough to allow gas from the super-heater to escape through the notches 39 of the scallops. The gas as it passes upward through the coke, 70 sprayed with the water from pipe 37, is cleaned and washed of certain of its impurities to a fairly pure state, such impurities and undesirable matter being caught in the trap 36. 75

A pipe 40 connects tank 32 with a second smaller tank 41, and between the pipe 40 and latter tank 41 is interposed a housing 40^a in which is a blower. Briefly, the blower is a shaft with a spirally formed blade or 90 blades 40^b with a belt pulley F for connection with the source of power which operates the machine. The purpose of the blower is to pull or suck the gas from the tank 32, and necessarily from the super-heater 29, 95 and connections through pipe 40 into the tank 41 and force the gas outward through the machine.

Tank 41 is divided into several sections 42 with gratings 43 therebetween and provided with doors 44. This tank contains hay or analogous matter and further cleans and dries the gas. 100

Connecting the pipe 40 and a pipe 46 (referred to further on) is a valved by-pass 105 pipe 45. The purpose of the pipe 45 is to provide a means for taking care of any excess pressure of gas above the normal production or as a regulating means and safety device. Thus, when the gas production 110 reaches beyond a certain predetermined flow or pressure (indicated by a gauge not shown) the valve 45^a, normally closed, will automatically open and the increased or surplus gas will pass back through the neck 115 of pipe 46 through the by-pass pipe 45, thence through pipe 40, blower 40^b and into the tank 41 again and will continue this circuitous passage until normal pressure is again reached, whereupon the valve 45^a will 120 close. A normal amount of gas, however, has in the meantime continued to pass out through pipe 46.

From tank 41 the gas is carried by pipe 46 to a horizontal spirally bladed conveyor 125 47 in a housing 48, the conveyor being rotated by suitable power connected to a pulley 49. The revolving blades of the conveyor whip the gas thoroughly dry from any remaining moisture which falls into the 130

trap 50 and is drained off by pipe 51. Moisture from tank 44 is conveyed by pipe 52 to trap 36. Gas ready for use or storage is carried from the housing or cylinder 48 by pipe 53.

In operation, fuel is fed to the container 14 through the hopper 15 and as the fuel is consumed a fresh charge is delivered to the container by rotation of the section 16 of the fuel measure as previously explained.

A fire having been started on the grate 6^a to ignite the fuel, the worm 28 is thrown into gear by the clutch, imparting rotation to the container 14 and to the feeder 8^a.

Fuel will then gravitate from the container 14 to the feeder 8^a and through the hoods 10 to the fire bed. The rotation of the feeder and hoods will distribute the fuel evenly over the fire bed, or grate which is also rotated at the same time. The conical upstanding grate will allow the clinkers to roll by gravity upon the platform 6. Owing to the formation and structure of the grate a better draft is provided than by a horizontal structure, the draft being further improved by the draft chamber A. The steam pipe E is for the purpose of injecting steam or vapor through the auxiliary draft chamber A which is designed to improve the quality of the gas.

Gases rising from the fire will be trapped in the upper portion of drum 8 from whence they will pass through pipes 30 to the superheater 29.

The intense heat of the super-heater will thoroughly dry the green gas and will gasify any particles of coal tar or creosote which may be contained in the gas and find its way through the pipes into the superheater.

From the super-heater 29 the gas is conducted through pipe 31 to tank 32 and passes upward through the water-drenched coke, is cooled and cleaned, the impurities being caught and retained in the trap 36.

From tank 32 the gas is conducted by pipe 40, drawn by the blower blades 40^b, to tank 41 where it is passed through the hay or other analogous matter and further cleaned, after which by pipe 46 the gas passes into the housing or cylinder 48 and "whipped" forced, or hurried therethrough in its final stage of purification, cleaning, cooling and drying, and the pure gas is ready for use

or storage and conducted away through pipe 53.

What is claimed is—

1. A gas producer comprising a drum providing a fire box and a retort, means for feeding fuel to the drum, a rotatable conical sectioned grate, a super-heater arranged in the drum in such a manner as to receive the maximum amount of heat from the fire, means for augmenting the draft, means for conducting the gas from the upper portion of the drum to the super-heater and means for conducting the gas from the super-heater.

2. A gas producer comprising a drum with a fire box and a retort, a water jacket surrounding the drum, means for feeding fuel to the drum, a conical grate carried upon and revolving with a platform, means for rotating the platform and grate, an auxiliary draft chamber underneath the grate, a steam pipe connected with the water jacket and extended into the auxiliary draft chamber, a super-heater with a restricted passage disposed within the drum in such a manner as to receive the maximum amount of heat from the fire; means for conducting gas from the drum to the super-heater and means for conducting gas from the super-heater to a cleaning, cooling and drying means.

3. A gas producer for producing gas from lignite, including a casing, a conical grate in the casing for receiving the lignite thereon, means to rotatably support the grate, means to superheat the gas located directly above the apex of the conical grate, means to conduct the gas from the superheating means to clean, cool and dry the same, and means for effecting rotation of the grate in order to maintain the under side of the lignite while on the grate and during combustion thereof in a substantially conical formation.

4. The herein described process for producing gas from lignite, which involves ignition of a bed of lignite of substantially cone shape on its under side and the constant rotation thereof to form gas, superheating the gas at a point adjacent to the apex of the under side of the bed, and then in conducting the gas after superheating to be cleaned, cooled and dried.

In testimony whereof I have signed my name to this specification.

ELBERT M. BRAXTON.
